UNITED STATES PATENT OFFICE

2,027,298

PORTABLE ELECTRIC LAMP

Grant Wheat, Marlboro, Mass., assignor to
Kochler Manufacturing Company, Marlboro, Mass., a corporation of Massachusetts

Application June 3, 1932, Serial No. 615,115

5 Claims. (Cl. 240—11.3)

This invention relates to portable electric lamp apparatus of the general type shown in my prior Patents Nos. 1,757,887, 1,757,888 and 1,757,889. While lamp structures of this general type were developed originally for use by miners, they have gone into rather general use in other lines, either in approximately the forms illustrated in the patents or in modifications embodying essentially the same ideas.

10 The most common commercial form of this apparatus consists of a headpiece or lamp casing adapted to be worn on the cap or carried on the person, one or more incandescent electric lamps mounted in said headpiece, a storage battery 5 which usually is slung from the wearer's body, and electric conductors operatively connecting said battery with said headpiece. A hand lamp, also, in which essentially the same features are involved, has come to be an important commercial 15 product. In view of the fact that these lamp structures are designed primarily for use in mines where they must be expected to operate in explosive atmospheres, it is extremely important that precautions be taken to prevent any possibility of a spark occurring under such conditions 20 that it could ignite a combustible gaseous mixture. Such sparks may be produced occasionally as an incident to the normal operation of the apparatus, or accidentally, due to the breakage 25 of some part, or even by the mischievous tampering or experimenting with the apparatus frequently indulged in by the miners themselves.

It is the general object of the present invention further to improve and perfect lamp structures of this nature with a view to improving their efficiency, increasing their serviceability, facilitating the charging of the batteries, and reducing the danger of injury to the apparatus due to tampering, or corrosion of the parts.

30 The nature of the invention will be readily understood from the following description when read in connection with the accompanying drawings, and the novel features will be particularly pointed out in the appended claims.

45 In the drawings,

Figure 1 is a perspective view of a lamp structure embodying features of this invention;

Fig. 2 is a diagram of the circuit connections of the apparatus shown in Fig. 1;

50 Fig. 3 is a front view of the headpiece;

Fig. 4 is a view partly in vertical section and partly in side elevation of the headpiece.

Figs. 5 and 6 are front and side views respectively of the reflector used in the headpiece 55 shown in Figs. 3 and 4.

Fig. 7 is a perspective view of the headpiece shown in Figs. 1 and 4 but with the bezel lens reflector and main lamp removed.

Fig. 8 is a detailed view of the devices for supporting the emergency lamp.

Referring first to Fig. 1, the lamp structure there shown comprises a headpiece or lamp casing 2 equipped with a spring actuated clamping device 3 for gripping the edges of a metal plate 4 which is secured to the front of a miner's cap 5 so as to hold the headpiece securely on the cap. A cable 6, including suitable electric conductors, operatively connects this headpiece with a storage battery 7 slung from the wearer's belt 8. In these general respects this lamp organization 15 is like that shown in my prior patents.

As above stated, it is one of the objects of this invention to improve the efficiency of apparatus of this type, having reference particularly to the illumination obtainable from a lamp of a given wattage. Preferably a single main lamp or working lamp 10, Figs. 3 and 4, is mounted in the headpiece and an emergency lamp 12 of a much smaller candle power than the main lamp is also carried by the headpiece to give the miner sufficient illumination to get out of the mine in the event that his main lamp bulb breaks. For example, the main lamp may have a beam candle power of 20, or even more, while the emergency lamp may be of perhaps 2 to 4 beam candle power. 20 The present invention provides an arrangement 25 whereby a larger proportion of the surface of the reflector is used than in prior constructions of the type in which both a main lamp and an emergency lamp are employed, while at the same time 30 permitting the use of either a standard or a special lamp bulb, as desired. 35

Referring more especially to Figs. 3 and 4, it will be observed that the main lamp 10 is mounted immediately in front of a concave reflector 13, the detailed construction of which is better illustrated in Figs. 5 and 6. Preferably, although not necessarily, the lamp 10 is of a special type having a standard base 14 which is provided with two pins projecting from diametrically opposite 45 points thereon, one of these pins being shown in Fig. 4 at 15. It is preferable, also, to use a main lamp having two filaments 16 and 17, Fig. 4, and consequently, this lamp is provided with two end terminals 18 and 19, respectively, these terminals 50 being connected to the respective leading-in wires 20 and 21, while the middle lead wire 22 is electrically connected to the metal base 14. Two leaf springs 24 and 25 are secured in the headpiece 2 with their ends in position to bear, respectively, 55

on the terminals 18 and 19 for the purpose of conducting current to one or the other of the filaments, as desired. The lamp base is positioned angularly by a forked spring 26, best shown in Fig. 7, which is secured in the headpiece 2, the arms of this spring straddling the lamp base 14 and having sockets or depressions, as clearly shown in Figs. 4 and 7, to receive the pins 15. In order to support the lamp bulb against the pressure of the springs 24, 25, 26, a strong spring arm 27 is secured firmly at one end to the casing and has its forward end forked and curved, as shown in Figs. 3, 4 and 7, to partly embrace the lower end of the bulb 10 and to support this bulb, while at the same time holding it back against the reflector 13.

In the event that the bulb 10 should be broken, the spring 26, which is constantly held under tension, will force the lamp base 14 downwardly, thus breaking the engagement of the terminals 18 and 19 with the contacts 24 and 25 so that any flow of current through the lamp will be instantly cut off. The contacts 24 and 25 have a relatively limited range of movement while the spring 26 can move through a considerable distance.

It will be observed that when this apparatus is in operation the spring arm 27 will cast a shadow on a part of the lower surface of the reflector 13. Advantage is taken of this fact to mount the emergency bulb 12 in this shadow. Also, in order to reduce the unused area of the reflector so far as possible, the bulb 12 is located chiefly behind the reflector and a hole 28, Fig. 5, is cut through it to admit light from the bulb 12. This bulb is of a standard construction, as shown in Fig. 8, and the hole 28 is smaller in diameter than the bulb so that the filament is located entirely behind the reflector, also the useful area of the reflector is made larger. The bulb is held in its socket by a forked or cupped spring arm 30, the socket comprising spring contact pieces 31 and 32, and the former having a hole therethrough so that it engages only the metal base of the bulb, while the latter engages simply the end terminal of the bulb. Consequently, if this lamp bulb should break, the spring terminal 31 would throw the base away from the terminal 32 and thus stop any flow of current through the circuit of the emergency lamp.

The mounting of the emergency lamp in the manner above described increases the useful area of the reflector while still making the small lamp 12 available for emergency use. Preferably the hole 28 includes a slot extending from the upper side thereof through which the arm 27 can project.

An electric switch is mounted in the headpiece to enable the operator to use either filament 16 or 17 of the main lamp, or to turn on the emergency lamp 12, as he may desire. Referring to Fig. 7 it will be seen that this switch comprises a movable switch arm 33 arranged to engage with the ends of either of the contacts 24 or 25, or with another contact 34 which is connected to the spring contact 31 for the emergency lamp. This switch arm 33 is secured on a short shaft on the outer end of which a switch button is fixed, or with which it is made integral.

It should be noted that the two filaments 16 and 17 of the main lamp bulb 10 are arranged approximately in a single straight line. While both filaments are coiled, the radius of the turns is very small so that for most practical purposes the filaments may be regarded as straight line

conductors. They are supported by leading-in wires 20, 21 and 22. When such a lamp is in operation these leading-in wires cast shadows on the reflector, thus producing darkened areas. In order to use the light afforded by the filaments, therefore, more efficiently, I prefer to so position the lamp that the straight line of the filaments 16 and 17 will coincide approximately with the axis of the reflector 13. This relationship is illustrated in Fig. 4. The lamp is held against rotation out of this position by the engagement of the pins 15—15 on the lamp base with the sockets in the arms of the spring 26. When the lamp is so positioned and either filament is lighted, it casts only one shadow on the reflector due to the fact that all of the leading-in wires are arranged in approximately the same vertical plane, this plane passing through the axis of the reflector. In addition to producing this advantage, such an arrangement also positions the filament 20 in the best geometrical relationship to the reflector when considered from an illuminating standpoint.

Double filament lamps of the character illustrated in Fig. 4 cost only slightly more than a single filament lamp having a rated life of two hundred hours. They can be obtained with two "regular" filaments each having a life of approximately two hundred hours so that a single bulb will have a total life of approximately four hundred hours. Or, such lamps may be purchased in which the filaments will have a higher efficiency and will give more light, but each filament will have a life of only approximately one hundred hours. Such a lamp is of advantage where a greater volume of light from a given battery is desired. In addition, these lamps can also be obtained in which one filament is of the regular two hundred hour variety, while the other has a shorter life, takes a higher amperage, and gives a greater candle power. Any of these lamps can be used successfully in the apparatus shown and, in addition, a lamp of this type can be used which has one service filament and an emergency filament. The latter, however, usually is not desired because of the fact that the apparatus customarily is equipped with an emergency bulb 12.

The headpiece or lamp casing 2 may be made of metal, vulcanite, bakelite, or any other suitable material. It has an open end which normally is closed by a "lens" 37, the term lens being here used in its common trade sense as distinguished from a strict or scientific sense, since this part 37 rarely is given the shape of a true lens. A bezel 38 screwed on to the main body of the headpiece holds the lens in place, a rubber gasket 40 preferably being interposed between the lens and the end of the casing or head piece. In order to assist in positioning this gasket I have bent the margin of the reflector 13 outwardly to form an annular flange 41, Fig. 5, and shaped the inner portion of this flange in the form of an annular bead 42. The gasket 40 encircles this bead so that the latter assists in holding the gasket properly centered. Lugs 43—43 are bent backwardly from the flange 41 and extend into depressions 44—44, Fig. 7, in the casing to prevent the reflector from turning when the bezel is screwed into position or is unscrewed to remove it.

For convenience in charging the battery, charging terminals 51—51, Figs. 2 and 4, are located on the neck or shank of the headpiece, as shown in one of my earlier patents above designated. It will be evident that if these terminals were con-

tinuously connected with the battery it would be possible for the miner to short circuit them, either accidentally or intentionally. Consequently, these terminals are connected to the battery through a switch which is normally held open. In order to reduce the duties of the attendant at the lamp house, and, in fact, to avoid the necessity for an attendant in the lamp house of a small mine, it is of advantage to provide such an arrangement that the miner can place his lamp in the charging rack as he leaves the mine and make the proper adjustments to put the battery on charge. These requirements are satisfied in the construction shown by providing a control circuit for automatically closing the normally open switch above mentioned when the lamp is properly placed in the charging rack and a charging potential is applied to the two charging terminals 51—51.

20 Referring more particularly to Figs. 2 and 7, it will be seen that the switch arm 33, previously mentioned, is arranged to engage an additional contact 52 which is connected with one of the charging terminals 51. The switch 33 is continuously connected with one terminal of the battery. The other battery terminal is connected through a thermostatic switch 53 to the other charging terminal 51. This switch includes a bimetallic strip 54 around which is wound a coil 55 of resistance wire. The strip carries a contact 56 adapted to engage a stationary contact 51 which is carried by, but is insulated from, the switch base. A casing encloses the switch parts. Normally the bimetallic strip 54 is warped or sprung to such an extent that it holds the contact 56 out of engagement with the contact 51 and, consequently, maintains the charging circuit open. As soon, however, as the lamp is properly placed in the charging rack, a current flows from one charging terminal 51 through the resistance coil 55 and the thermostatic switch 54 back to the other charging terminal. This raises the temperature of the thermostatic switch and causes its free end to swing toward the stationary contact 57, thus closing the switch. If the manually operated switch 33 has previously, or is now, moved to bring its arm 33 into engagement with the contact 52, a charging current will then flow through the battery 1. When the miner takes his lamp out of the charging rack in the morning, it is simply necessary for him to turn the switch arm 33 far enough to light one of the filaments 16 or 17, and he can then go to work. The bi-metallic strip 54 cools off rapidly and opens the thermostatic switch very shortly after the lamp has been removed from the charging rack, and switch arm is turned.

60 This construction, therefore, enables the miner to recharge his own lamp, and in many mines makes it unnecessary to keep a man on duty at the lamp house.

65 The invention thus provides a portable lamp structure which is practically foolproof, is very convenient to operate and can readily be adapted to a great variety of conditions such as the intensity of the light desired, length of service afforded, and other practical requirements of the user. Many of the features of this invention can also be used in hand lamps.

70 While I have herein shown and described a preferred embodiment of my invention, it will be understood that the invention may be embodied in other forms without departing from the spirit or scope thereof.

75 The novel features of the construction designed

to facilitate charging and to prevent short circuiting of the battery by the accidental or intentional connection of the exposed charging terminals are not claimed here but are claimed in a divisional application Serial No. 712,739, filed February 24, 1934. 5

Having thus described my invention, what I desire to claim as new is:

1. In a portable lamp structure, the combination of a headpiece, a main electric lamp bulb 10 mounted in said headpiece, a reflector in said headpiece behind said bulb, a lens supported in said headpiece at the opposite side of said bulb from said reflector, said lens closing the normally open end of the headpiece, means for supporting said bulb with its axis lying approximately parallel to said lens and with the filament of the lamp approximately centered with reference to said reflector, the base of said lamp projecting through a hole in said reflector, a spring arm engaging said bulb of said lamp to assist in holding said bulb in its operative position, and an emergency lamp of a smaller candle power than said main lamp located chiefly behind said reflector, said spring arm being positioned between said emergency lamp and said main lamp bulb. 20

2. In a portable lamp structure, the combination of a headpiece, a main electric lamp mounted in said headpiece, a socket in which the base of said lamp is mounted, a reflector in said headpiece behind the bulb of said lamp, an arm projecting in front of said reflector for engaging the lamp bulb and cooperating with said socket to hold said lamp in its operative position, an emergency electric lamp of a smaller candle power than said main lamp, and means for supporting said emergency lamp with its bulb in the shadow of said arm. 30

3. In a portable lamp structure, the combination of a headpiece, a main electric lamp mounted in said headpiece, a socket in which the base of said lamp is mounted, a reflector in said headpiece behind the bulb of said lamp, an arm projecting in front of said reflector for engaging the lamp bulb and cooperating with said socket to hold said lamp in its operative position, an emergency electric lamp of a smaller candle power than said main lamp, and means for supporting said emergency lamp in said headpiece and positioned chiefly behind said reflector, said reflector having an aperture for the passage of light from said emergency lamp, said aperture being located in the shadow of said arm. 40

4. In a portable lamp structure, the combination of a headpiece, a main electric lamp mounted in said headpiece, a socket in which the base of said lamp is mounted, a reflector in said headpiece behind the bulb of said lamp, an arm projecting in front of said reflector for engaging the lamp bulb and cooperating with said socket to hold said lamp in its operative position, an emergency electric lamp of a smaller candle power than said main lamp, and means for supporting said emergency lamp in said headpiece and positioned chiefly behind said reflector, said reflector having an aperture for the passage of light from said emergency lamp, said arm being secured to said headpiece and projecting through said aperture and said aperture being located in the shadow of said arm. 50

5. In a miner's lamp, the combination of a headpiece, an electric lamp bulb mounted in said headpiece, a concave reflector in said headpiece, said lamp having two filaments both arranged substantially in a single straight line extending 60

at approximately right angles to the axis of said lamp bulb, means for supporting said lamp bulb with the line of said filaments lying approximately in and coincident with the axis of said reflector, said lamp supporting means comprising resilient means engaging the globe of the bulb, and resilient electrical connections engag-

ing the terminals on the base of said lamp bulb, a switch mounted in said headpiece, and supply conductors associated with said terminals and said switch to enable the miner to turn the current on or off either of said filaments at will. 5

GRANT WHEAT.
